UNITED STATES PATENT OFFICE.

LELIA DOWNES-MARTIN, OF CHRISTCHURCH, ENGLAND.

MATCH BOX, ASH TRAY, AND OTHER BOXES AND TRAYS.

Application filed April 27, 1926, Serial No. 104,991, and in Great Britain October 1, 1925.

This invention relates to match-boxes, ash-trays, and other like boxes and trays.

The object of this invention is to provide an improved combined box and tray for 5 matches and other articles.

A combined box and tray made in accordance with this invention comprises a box adapted to be opened and closed in any well known manner and a casing adapted to be 10 folded over said box when in its closed position, and to be opened out to form a tray when desired.

Referring to the drawings filed here-with:—

Fig. 1 is a perspective view of one form 15 of combined box and tray made in accordance with this invention in its closed position;

Fig. 2 is a perspective view of the same 20 device in its open position.

a is the box, *b* the bottom of the box, *c* is a casing which may have a separate bottom, or the bottom of the casing may be the bottom of the box. The casing has four 25 sides *c c*, with flexible folds or hinges along the edges marked *d d*. The corners of the tray are connected together by flexible material to form webs *e e*. The sides *c c* of the casing are connected by rubber or elastic strips *f f* to permit of the casing being moved from the closed to the open position.

What I claim and desire to secure by Letters Patent is:—

1. A box comprising an outer casing, a

tray or drawer adapted to fit inside the 35 casing, and members hingeably affixed to the casing, the said members constituting a tray in the open position and adapted to be folded over the sides of the casing when not in use.

2. A box comprising an outer casing, a 40 tray or drawer adapted to fit inside the casing, and a collapsible tray having four sides hingeably secured to the top of the casing, the said sides being adapted in one 45 position to form a tray and in another position to be folded down over the sides of the casing.

3. A box comprising an outer casing, a 50 tray or drawer adapted to fit inside the casing, and a collapsible tray having four sides hingeably secured to the top of the casing. the sides being connected together at the corners by a flexible material to permit them over the sides of the casing.

4. A box comprising an outer casing, a 55 tray or drawer adapted to fit inside the casing, and a collapsible tray having four sides hingeably secured to the top of the casing, 60 the sides being connected together at the corners by a flexible material to permit them to be folded down, when not in use as a tray, over the sides of the casing, and by elastic strips to retain the sides in the open or closed 65 position.

In testimony whereof I affix my signature.

LELIA DOWNES-MARTIN.
